DESIGN FOR A MARMALADE JAR

Charles Kaiser, Great Neck, N. Y., assignor to Morimura Bros. Inc., New York, N. Y., a corporation of Japan

Application September 1, 1934, Serial No. 53,153

Term of patent 7 years

To all whom it may concern:

Be it known that I, Charles Kaiser, a citizen of the United States, and a resident of Great Neck, county of Nassau, and State of New York, have invented a new, original, and ornamental Design for a Marmalade Jar, of which the following is a specification, reference being had to the accompanying drawing, forming part hereof.

In the drawing, Figure 1 is an elevation of a marmalade jar showing my new design, and Figure 2 is a plan view thereof, it being understood that the ornamentation shown above the dotted line will be repeated in the lower half of the cover or below the dotted line, in the same relation as the portion of the design above the dotted line.

I claim:

The ornamental design for a marmalade jar, as shown and described.

CHARLES KAISER.
